AUTOMATIC VALVE AND SYSTEM

Homer E. Thornhill, Houston, Tex., assignor to
 Thornhill-Craver Company, Inc., Houston,
 Tex., a corporation of Texas

Application March 2, 1949, Serial No. 79,123

25 Claims. (Cl. 137—460)

1

This invention pertains to automatic valves, and more particularly to automatic shut-off valves for petroleum pipe lines.

Usually a petroleum oil and gas well is located at a considerable distance from the collection and storage tank to which it is connected. The connecting pipe may run under, on or over ground, water or roads, in fact it may chance to be most anywhere. It is therefore constantly subject to breakage from passage thereover of ships, tractors, trucks, or by snagging anchors, plows, or chains. In addition, it may burst due to excessive well pressure. In any event, a break will constitute a hazard at the point of breakage due to the inflammable and explosive nature of the substance. In addition, there is considerable economic waste due to the loss of oil and gas through the break.

It is the principal object of this invention to provide a valve and control system for automatically closing in a well either in case of excessive pipe line pressure which might cause the pipe to break or in case of an actual break due to any cause.

It is a further object of the invention to provide a valve and control system of the aforesaid type which will keep the well closed in once it has been closed in until the valve system is manually reopened.

It is another object of the invention to provide such a valve and control system which will automatically indicate the position of the valve, that is, whether open or shut.

Another object of the invention is to provide a valve and control system therefor which will cause the valve to close automatically upon either an excessive rise of downstream pressure or an excessive fall of downstream pressure.

Still another object of the invention is to provide such a valve and system that can easily be added to existing installations with a minimum of time, effort and expense.

A further object of the invention is to provide such a valve and control system which will be simple and reliable in operation.

Another object of the invention is to provide such a valve and control system which will be inexpensive to manufacture and economical to operate.

A further object of the invention is to provide such a valve and control system that will occupy a minimum amount of space.

Briefly, the invention comprises a valve element which can replace the valve element of the

2

usual adjustable choke or wing valve on the Christmas tree just upstream from the positive choke. The valve stem passes through a packing gland and is connected to a large piston traveling in a large cylinder and beyond that to a small piston traveling in a small cylinder. The far end of the small cylinder is always connected to the upstream side of the valve and exerts a pressure tending to close the valve. The large cylinder, at a point close to the end thereof nearest the valve, is always connected through a small choke to the pipe line downstream of the valve and positive choke. Normally the valve is open and the areas of the two pistons are so related to the upstream and downstream pressures that the valve is held open. Upon a drop in downstream pressure, however, the valve will be closed. As the valve approaches closed position an auxiliary valve in an atmospheric exhaust line leading to another port connected to the extreme near end of the large cylinder will open, thus further dropping the pressure in the large cylinder. Near the end of the movement the large piston itself blocks off the port leading to the downstream line so that even if the pressure should return to normal the valve would stay closed. Because of this construction, whenever the valve is closed the pressure in the large cylinder is atmospheric.

The extreme near end of the large cylinder is also connected through a manually operated three-way valve to another atmospheric exhaust line. The latter is normally closed by a pop valve set to open at a predetermined pressure. Upon an excessive increase in the downstream pressure the pop valve will open causing a drop in pressure in the large cylinder and the main valve will close the same as though there were a drop in the downstream pressure. The small choke in the line from the pipe line to the large cylinder insures that there will be a sufficient drop in pressure in the large cylinder under these conditions.

A hand operated bleeder valve controls a branch line from the line controlled by the pop valve. If it is desired to close the main valve the bleeder valve is opened, which drops the pressure in the large cylinder the same as if the pop valve had opened.

If it is desired to open the main valve, which must always be done manually, the above-mentioned three-way valve is turned so as to connect the large cylinder to a line from the upstream side of the main valve instead of the pop valve controlled atmospheric exhaust line. This brings the

pressure in the large cylinder up nearly to that in the small cylinder, the other lines leading from the large cylinder being small enough to serve as chokes, so that the force of the small cylinder is overbalanced and the valve opened. Returning the three-way valve to its previous position makes the system responsive again, in which condition any excessive drop in pressure in the large cylinder will cause it to close. Such a drop may occur in any of three ways: manual opening of the bleed valve, automatic opening of the pop valve on excessive pressure, or breakage of the downstream line causing an excessive drop in pressure. A pressure gauge is also connected to the exhaust line leading to the pop valve from the large cylinder. If the gauge shows that there is pressure in the cylinder, it indicates the main valve is open. If the gauge shows atmospheric pressure, the main valve is closed.

One of the principal advantages of the invention lies in the fact that no springs are used, except perhaps on the pop valve, and even here the spring can be eliminated by substituting a weight. Springs are very undesirable in a valve of this sort due to the presence of sand, shale, dust, paraffin, hydrogen and other substances in the crude petroleum. Hydrogen absorption embrittles the springs and causes them to break. Sand and other substances are apt to cause the springs to stick.

Another advantage lies in the fact that only a small amount of gas is used to operate the valve. There is no continuous flow of gas and therefore little likelihood of freezing.

Other objects and advantages of the invention will appear from the following detailed description of a preferred embodiment thereof in which:

Figure 1 is a section taken along the axis of the valve; and

Figures 2, 3, and 4 are schematic drawings of the control system showing the valve open and responsive, closed, and manually opened, respectively.

Figures 5, 6, and 7 show a four-way valve suitable for use in the system.

Referring now to Figure 1, the valve comprises a valve body 1 having a threaded inlet 2 adapted to be connected to a side arm of a Christmas tree manifold. The valve body also has a flanged outlet 3 adapted to be connected to a positive choke from which leads the pipe line going to the storage tank. The valve body is in the shape of a T, the inlet 2 being at the base of the T, and the outlet 3 being in one of the arms of the T. Through the other arm of the T projects a valve stem 4 on which is mounted the valve 5 which cooperates with a removable valve seat 6 threadedly supported within the outlet 3. The valve stem 4 is slidably supported within the center of the arm of the T opposite the outlet by means of a flanged valve bonnet 7. The valve bonnet is sealed to the end of the valve body by means of a steel ring gasket 8 and is secured thereto by means of a fast coupling 9.

The valve bonnet is provided with two cylindrical bearings 10 and 11 for supporting the cylindrical valve stem 4. Within each of the two annular grooves 12 and 13 within the bearings 10 and 11 there is mounted a neoprene O ring such as that shown at 14 disposed between a pair of leather non-extrusion rings such as that shown at 15. These form a pair of spaced sliding seals between the valve stem 4 and the valve bonnet 7.

An actuating cylinder 20 is connected to the outer end of the valve bonnet 7 by means of screw

thread 21 and is sealed thereto with a neoprene O ring 22. The cylinder is provided with a large bore 23 within which slides cylindrical piston 24 connected to the outer end of the valve stem 4. Within an annular groove 25 on the periphery of the piston 24 is disposed a neoprene O ring 26. The O ring is placed between two leather non-extrusion rings, such as that shown in 27. These rings form a seal between the piston and the cylinder walls. Similar O rings and non-extrusion rings placed in a second annular groove 28 in the periphery of the piston 24 provide a second sliding seal between the piston and cylinder walls.

A small piston 30 is threadedly connected at 31 within an aperture in the end of piston 24 opposite the valve stem and is sealed thereto by means of neoprene O ring 32. Cylindrical piston 30 travels within cylindrical bore 33 in a small cylinder 34 telescoped within counterbore 35 in the end of cylinder 20 farthest from the valve bonnet. Cylinder 34 is held in place in the end of cylinder 20 by means of a snap ring 36 placed over the reduced end 37 of cylinder 34 and expanded into annular groove 38 within the end of counterbore 35. Cylinder 34 is sealed to cylinder 20 by means of O ring 39. An O ring and two leather non-extrusion rings placed in annular groove within the bore 33 of cylinder 34 provide a sliding seal between the small piston 30 and the small cylinder walls 33. This construction makes it possible to adapt the valve and control system to a particular set of operating pressures corresponding to a particular well and pipe line by changing the size of the high-pressure cylinder without having to change the rest of the valve control mechanism. It is only necessary to select the desired size cylinder 34 and lock it in place in the end of cylinder 20 and select a piston 30 to fit the cylinder 34 and screw it in place in the end of piston 24.

The valve stem 4 is provided with radial and axial bores 50 and 51 and piston 30 is provided with an axial bore 52. These, together with space 53 between the socket in large piston 24 and the screw plug end of small piston 30, form a continuous passage from the up-stream or high-pressure portion of the interior of the valve body 1 to the interior of the small or high-pressure cylinder 34. A port 54 in the end of the cylinder 20 and a screw socket 55 therein provide a passage from the interior of the small or high-pressure cylinder to the manually operated three-way valve. These internal passages through the valve eliminate the necessity for tapping into the Christmas tree in order to connect to the high-pressure fluid in the well which is used for urging the valve to closed position. It also reduces to a minimum the amount of high-pressure tubing needed for the control system.

A radial port 60 and a longitudinal passage 61 connect the interior of the large or low-pressure cylinder 20 to a screw socket 62 in the end of the cylinder body 20 adapted to receive a small choke plug. The other side of the choke plug will be connected through a control line to the pipe line on the down-stream or low-pressure side of the positive choke. If desired the choke may be a small hole drilled in the body rather than being added as an accessory or the port 60 and passage 61 may be small enough to serve as a choke themselves. However, the removable choke makes the apparatus more adaptable to changed operating pressures.

As shown in the drawings, when the valve is in the closed position the piston 24 blocks off

the end of passage 60, thereby preventing the low-pressure fluid from the pipe line getting between the piston 24 and the end of the cylinder 20 nearest the valve. When the valve is opened a small amount of port 60 is uncovered and admits low-pressure fluid to this space so as to urge the valve towards its open position. Thus port 60 and piston 24 constitute a secondary valve means for controlling fluid flow in the low-pressure control line. Under normal conditions the force exerted by this low-pressure fluid on piston 24 is greater than the force exerted by the high-pressure fluid on the end of piston 30, so that the main valve stays open.

Radial passage 70 and longitudinal passages 71 and 72 in the walls of the cylinder 20 provide a connection from the operating space in the low-pressure cylinder between piston 24 and the end of the cylinder nearest the valve to a screw socket 75 in the end of cylinder body 20. A screw plug in the socket 75 will connect these passages to a control pipe leading to the three-way valve. In the normal position of the three-way valve, the control pipe will in turn be connected to another control pipe leading to the manual bleed valve, the pressure gauge, and the excess-pressure pop valve. The pop valve is constructed to reclose at a lower pressure than that at which it opens. If the bleed valve should be manually opened, or if the pop valve should open because of excessive pressure in the pipe line downstream from the positive choke, the pressure in the operating space of the low-pressure cylinder will fall, permitting the valve to be closed by the high-pressure fluid in the small cylinder. The same thing would occur if there should be a fall in pressure in the pipe line due to breakage or other cause. The pressure gauge indicates the position of the valve.

A radial port 80, a longitudinal bore 81, and a radial port 83 connect the operating space of the low-pressure cylinder to an annular space 84 within the valve bonnet 7 between the bearings 10 and 11. A passage 85 connects space 84 to atmosphere. When the valve is in its normal or open position, the end of port 83 will be blocked off by bearing 11. Whenever the valve moves a short distance toward its closed position, due to any of the previously mentioned causes, the port 83 will be opened, allowing the low-pressure fluid in the operating space of cylinder 20 to exhaust to the atmosphere. In order to drill the bore 81, it is continued through to the end of piston 24 opposite the valve. The end of the passage is blocked off afterwards with weld metal, as indicated at 86. If desired a tapered pin could be driven in to close the passage instead. The port 83 and bearing 11 constitute the auxiliary valve actuated by the main valve referred to in the brief introductory description of the invention. The port 80 is drilled to the proper size to prevent the low-pressure fluid from exhausting too fast. This keeps the valve from slamming shut. If desired a removable choke plug could be used here to adapt the apparatus to different operating pressures.

Because of the fact that the large cylinder 20 also houses the small cylinder 34, there is a possibility that despite the seals between the cylinders and the pistons operating therein fluid under pressure may leak into the space between the large piston 24 and the inner end of the small cylinder 34. Such an accumulation on the back-side of piston 24 would render the system and valve inoperative. To prevent this from happen-

ing, the cylinder 20 is provided with one or more vents such as the radial bore 81.

Assuming the valve to be in the closed position as shown in the drawings, if it desired to open the valve this can be accomplished by connecting the pipe from the socket 55 with the control pipe from the socket 73. This can be done by changing the position of the three-way valve. This admits high-pressure fluid to the operating space of the low-pressure cylinder, thereby overcoming the force in the high-pressure cylinder tending to keep the valve closed. The exhaust passage 81 from the low-pressure cylinder to atmosphere is of sufficiently small size so that enough pressure can build up in the low-pressure cylinder under these conditions to open the valve. After the valve has been opened the three-way valve is returned to its original position, in which the control pipe connected to the socket 55 is closed off and the control pipe connected to the socket 73 is in communication with the pop valve.

Referring now to Figure 2, there is shown a schematic representation of a well and pipe line system, together with the automatic shut-off valve and the control system therefor. The main pipe line system is shown in heavy lines. The control lines leading to the shut-off valve are shown in light lines. The well 100 is connected through master valve 101 of the Christmas tree to automatic shut-off valve 102. The outlet of shut-off valve 102 leads to positive choke 103, which, in turn, is connected to the pipe line 104 leading to a suitable separator and thence to storage tank 105.

The control system comprises high-pressure control line 106 leading from the high-pressure side of the positive choke to the high-pressure cylinder 34. (In the construction shown in Figure 1, the high-pressure line 106 is constituted by the passages 50, 51 and 52 through the valve stem and pistons.) The low-pressure cylinder 20 is connected through a small choke 107 and low-pressure control line 108 to the low-pressure side of the positive choke 103. The extreme end of low-pressure cylinder 20 is connected to atmosphere through auxiliary valve 109. (In the construction shown in Figure 1 the auxiliary valve 109 is constituted by the port 83 in the valve stem and the bearing 11 for the valve stem.) The extreme end of the low-pressure cylinder 20 is also connected through control line 110 and three-way valve 111 to an exhaust line 112. The exhaust line 112 is normally closed by a pop valve 113. Also connected to exhaust line 112 is a bleed line 114 controlled by a manual valve 115. A pressure gauge 116 is also connected to the exhaust line 112. The third port in the three-way valve is connected through control line 117 to the high-pressure control line 106.

In Figure 2 the control system and valve are shown in the open and responsive positions. In Figure 3 the valve is shown closed. This might be brought about by a break in the line at A or an excessive pressure in the line A causing the pop valve to open at B or by a manual opening of the bleeder valve at C.

Figure 4 illustrates how the valve may be reopened manually by changing the position of the three-way valve 111 so as to connect the control line 110 from the low-pressure cylinder through the control line 117 to the high-pressure control line 106. After the valve has been reopened, the three-way valve 111 is returned to the position shown in Figure 2 to render the system responsive.

If desired the three-way valve 111 and the manual valve 115 can be combined into a single four-way valve 111A shown in Figure 5. As shown the valve is in normal position connecting line 110 to pop valve controlled exhaust line 112. Turning the valve to the right as shown in Figure 6 connects line 110 to atmospheric bleed line 114A to manually close the main valve while keeping the high-pressure line 117 shut off. At the same time the connection to the pop valve controlled line 112 preferably stays open to insure that the gauge pressure drops to atmospheric to show that the valve is closed. Turning the valve to the left as shown in Figure 7 connects line 110 to high-pressure line 117 to manually open the valve while shutting off the pop valve controlled exhaust line 112 and the atmospheric bleed line 114A.

When a well is first brought in it may be desired to use an adjustable choke to determine the size choke needed for a given flow. The adjustable choke may comprise a manually operated valve disposed in the valve body 2 replacing the automatic valve shown in Figure 1. After the desired size choke has been determined, the proper size flow bean may be placed in the positive choke 102 shown in Figures 2, 3 and 4. Then, with the master valve 101 still shut off, the fast coupling 9 between the valve body 2 and the adjustable choke valve can be released, the adjustable choke valve replaced with the automatic valve, and the fast coupling replaced as shown in Figure 1. Thereafter reopening the master valve 101 will place the system into production.

While a preferred embodiment of the invention has been illustrated and described, it is obvious that many modifications thereof could be made by one skilled in the art without departing from the spirit of the invention. It is desired to protect by Letters Patent all forms of the invention falling within the scope of the appended claims.

I claim:

1. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, exhaust means for connecting the second said chamber to the atmosphere, pressure responsive valve means in said exhaust means normally closing the exhaust means but adapted to open the exhaust means on increase in pressure above a predetermined amount, and three-way valve means disposed in said exhaust means between the second said chamber and said pressure responsive valve

means and also connected to said pipe line on the upstream side of said valve member, said three-way valve means in one position opening the connection in said exhaust means from the second said chamber to said pressure responsive valve means and in another position closing the last said connection and completing a through passage from the last said pipe line connection to the second said chamber.

2. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, relief means for connecting the second said chamber to atmosphere, and auxiliary valve means in said relief means interlocked with said movable wall of the second said chamber, said auxiliary valve means closing said relief means when the last said movable wall is in position corresponding to open position of said valve member and opening said relief means when the last said movable wall has moved away from its last said position.

3. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, relief means for connecting the second said chamber to atmosphere, auxiliary valve means in said relief means interlocked with said movable wall of the second said chamber, said auxiliary valve means closing said relief means when the last said movable wall is in position corresponding to open position of said valve member and opening said relief means when the last said movable wall has moved away from its last said position, and a pressure responsive de-

vice connected to the second said chamber to indicate the position of said valve member.

4. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, and secondary valve means controlling the last said means closing the connection when the movable wall of the second said chamber is in position corresponding to closed position of said valve member and opening the connection when the last said wall has moved away from its last said position.

5. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, secondary valve means controlling the last said means closing the connection when the movable wall of the second said chamber is in position corresponding to closed position of said valve member and opening the connection when the last said wall has moved away from its last said position, relief means for connecting the second said chamber to atmosphere, and auxiliary valve means disposed in said relief means interlocked with said movable wall of the second said chamber, said auxiliary valve means closing said relief means when the last said movable wall is in position corresponding to open position of said valve member and opening said relief means when the last said movable wall has moved away from the last said position, said auxiliary valve means opening said relief means upon movement of said wall of the second chamber toward the position corresponding to closed position of said valve member before said

secondary valve means closes said means connecting said chamber to the pipe line.

6. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, 10 closing means for moving the valve member to closed position including an expansible chamber having a movable wall, opening means for moving said valve member to open position comprising an expansible chamber having a movable wall, 15 the first said wall being of smaller area than the second said wall, means associating the two said walls and said valve member to cause movement of each of the three to at least tend to move at least one of the others with the movement of each 20 wall upon expansion of the chamber of which it is a part opposing like movement of the other wall, means for connecting the first said chamber to said pipe line on the upstream side of said valve member, means for connecting the second said chamber to the pipe line on the downstream side of said choke, the last said means including a choke, exhaust means for connecting the second said chamber to the atmosphere, and pressure responsive valve means in said exhaust 25 30 means normally closing the exhaust means but adapted to open the exhaust means on increase in pressure above a predetermined amount.

7. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, 35 closing means for moving the valve member to closed position including an expansible chamber having a movable wall, opening means for moving said valve member to open position comprising an expansible chamber having a movable 40 wall, the first said wall being of smaller area than the second said wall, means associating the two said walls and said valve member to cause movement of each of the three to at least tend to move at least one of the others with the movement of each 45 wall upon expansion of the chamber of which it is a part opposing like movement of the other wall, means for connecting the first said chamber to said pipe line on the upstream side of said valve member, means for connecting the second said chamber to the pipe line on the downstream side of said choke, relief means for connecting the second said chamber to atmosphere, auxiliary valve means in said relief means interlocked with said movable wall of the second 50 55 said chamber, said auxiliary valve means closing said relief means when the last said movable wall is in position corresponding to open position of said valve member and opening said relief means when the last said movable wall has moved away from its last said position, exhaust means for connecting the second said chamber to the atmosphere, pressure responsive valve means in said exhaust means normally closing the exhaust means but adapted to open the exhaust means on increase in pressure above a predetermined amount, and three-way valve means disposed in said exhaust means between the second said chamber and said pressure responsive valve means and also connected to said pipe line on the upstream side of said valve member, said 60 65 70 75

three-way valve means in one position opening the connection in said exhaust means from the second said chamber to said pressure responsive valve means and in another position closing the last said connection and completing a through passage from the last said pipe line connection to the second said chamber.

8. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expandible chamber having a movable wall, opening means for moving said valve member to open position comprising an expandible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, the last said means including a choke, secondary valve means controlling the last said means closing the connection when the movable wall of the second said chamber is in position corresponding to closed position of said valve member and opening the connection when the last said wall has moved away from its last said position, relief means for connecting the second said chamber to atmosphere, auxiliary valve means in said relief means interlocked with said movable wall of the second said chamber, said auxiliary valve means closing said relief means when the last said movable wall is in position corresponding to open position of said valve member and opening said relief means when the last said movable wall has moved away from its last said position, exhaust means for connecting the second said chamber to the atmosphere, pressure responsive valve means in said exhaust means normally closing the exhaust means but adapted to open the exhaust means on increase in pressure above a predetermined amount, and three-way valve means disposed in said exhaust means between the second said chamber and said pressure responsive valve means and also connected to said pipe line on the upstream side of said valve member said three-way valve means in one position opening the connection in said exhaust means from the second said chamber to said pressure responsive valve means and in another position closing the last said connection and completing a through passage from the last said pipe line connection to the second said chamber.

9. A pressure control apparatus comprising a valve member adapted to be placed in a hollow valve body having an inlet and outlet connected in a pipe line on the high-pressure side of a choke, said valve member being adapted in one position to close the passage through said body and in another position to open said passage, a valve stem connected to said valve member, closing means for moving the valve member to closed position including a cylinder of small cross-sectional area and a piston slidably axially therein,

opening means for moving the valve means to open position comprising a cylinder of large cross-sectional area and a piston slidably axially therein, said piston being associated with each other and said valve stem with their axes parallel so that said opening means opposes said closing means with respect to control of the position of the valve means, means for connecting the operating space in the small-area cylinder to said pipe line on the upstream side of said valve member, and means for connecting the operating space in the large-area cylinder to the pipe line on the downstream side of said choke, the last said means including a port in the wall of the large area cylinder, said port being closed by the piston in the large-area cylinder when the last said piston moves away from its position corresponding to full opening of the valve member.

10. A pressure control apparatus adapted to be connected to a valve body having an inlet and an outlet comprising a valve member adapted to be placed in said body to control the flow of fluid therethrough, a valve stem connected at one end to said valve member, a valve bonnet providing a sealing sliding support for said valve stem, a first cylinder connected to said valve bonnet, a first piston on the other end of said valve stem slidably disposed in said cylinder, a second cylinder of smaller diameter than the first cylinder connected to said first cylinder, a second piston connected to the said first piston and slidably disposed in said second cylinder, a passage through said valve stem and pistons adapted to connect the second cylinder with the interior of said valve body, and a port through the wall of the first cylinder closed by the first piston when said valve member is in valve closing position and open when said valve member is in valve opening position.

11. A pressure control apparatus adapted to be connected to a valve body having an inlet and an outlet comprising a valve member adapted to be placed in said body to control the flow of fluid therethrough, a valve stem connected at one end to said valve member, a valve bonnet providing a sealing sliding support for said valve stem, said support comprising two spaced seals and an annular chamber therebetween around said stem, a passage through said bonnet connecting said chamber to the atmosphere, a first cylinder connected to said valve bonnet, a first piston on the other end of said valve stem slidably disposed in said cylinder, a second cylinder of smaller diameter than the first cylinder connected to said first cylinder, a second piston connected to the first said piston and slidably disposed in said second cylinder, a passage adapted to connect the second cylinder with the interior of said valve body, a second passage through said valve stem for connecting the first cylinder with said annular chamber when said valve member has moved away from full open position, said second passage being blocked off by said bonnet when said valve member is in full open position, and a port through the wall of the first cylinder closed by the first piston when said valve member is in valve closing position and open when said valve member is in valve opening position.

12. A pressure control apparatus adapted to be connected to a valve body having an inlet and an outlet comprising a valve member adapted to be placed in said body to control the flow of fluid therethrough, a valve stem connected at one end to said valve member, a valve bonnet providing a sealing sliding support for said valve stem, said

support comprising two spaced seals and an annular chamber therebetween around said stem, a passage through said bonnet connecting said chamber to the atmosphere, a first cylinder connected to said valve bonnet, a first piston on the other end of said valve stem slidably disposed in said cylinder, a second cylinder of smaller diameter than the first cylinder connected to said first cylinder, a second piston connected to the first said piston and slidably disposed in said second cylinder, a passage through said valve stem and pistons adapted to connect the second cylinder with the interior of said valve body, a second passage through said valve stem for connecting the first cylinder with said annular chamber when said valve member has moved away from full open position, said second passage being blocked off by said bonnet when said valve member is in full open position, and a port through the wall of the first cylinder closed by the first piston when said valve member is in valve closing position and open when said valve member is in valve opening position.

13. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, exhaust means for connecting the second said chamber to the atmosphere, pressure responsive valve means in said exhaust means normally closing the exhaust means but adapted to open the exhaust means on increase in pressure above a predetermined amount, and four-way valve means disposed in said exhaust means between the second said chamber and said pressure responsive valve means and also connected to said pipe line on the upstream side of said valve member and further connected to an exhaust line, said four-way valve means in one position opening the connection in said exhaust means from the second said chamber to said pressure responsive valve means while closing the last said pipe line connection and exhaust line and in another position connecting the second said chamber to the last said pipe line connection while closing the exhaust means and exhaust line, and in still another position connecting the second said chamber to the exhaust line while closing the last said pipe line connection.

14. A pressure control apparatus comprising a valve member adapted to be placed in a hollow valve body having an inlet and an outlet connected in a pipe line on the high-pressure side of a choke, said valve member being adapted in one position to close the passage through said body

and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, the last said means including a choke, secondary valve means controlling the last said means closing the connection when the movable wall of the second said chamber is in position corresponding to closed position of said valve member and opening the connection when the last said wall has moved away from its last said position, relief means for connecting the second said chamber to atmosphere, auxiliary valve means in said relief means interlocked with said movable wall of the second said chamber, said auxiliary valve means closing said relief means when the last said movable wall is in position corresponding to open position of said valve member and opening said relief means when the last said movable wall has moved away from its last said position, exhaust means for connecting the second said chamber to the atmosphere, pressure responsive valve means in said exhaust means normally closing the exhaust means but adapted to open the exhaust means on increase in pressure above a predetermined amount, manual valve means in said exhaust means for opening the exhaust line when desired, a pressure responsive device connected to said exhaust means upstream from said pressure responsive valve means to indicate the position of said valve member, and three-way valve means disposed in said exhaust means between the second said chamber and said pressure responsive valve means and also connected to said pipe line on the upstream side of said valve member, said three-way valve means in one position opening the connection in said exhaust means from the second said chamber to said pressure responsive valve means and in another position closing the last said connection and completing a through passage from the last said pipe line connection to the second said chamber.

15. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall

wall, means for connecting the first said chamber to said pipe line on the upstream side of said valve member, means for connecting the second said chamber to the pipe line on the downstream side of said choke, the last said means including a choke, secondary valve means controlling the last said means closing the connection when the movable wall of the second said chamber is in position corresponding to closed position of said valve member and opening the connection when the last said wall has moved away from its last said position, relief means for connecting the second said chamber to atmosphere, auxiliary valve means in said relief means interlocked with said movable wall of the second said chamber, said auxiliary valve means closing said relief means when the last said movable wall is in position corresponding to open position of said valve member and opening said relief means when the last said movable wall has moved away from its last said position, exhaust means for connecting the second said chamber to the atmosphere, pressure responsive valve means in said exhaust means normally closing the exhaust means but adapted to open the exhaust means on increase in pressure above a predetermined amount, and four-way valve means disposed in said exhaust means between the second said chamber and said pressure responsive valve means and also connected to said pipe line on the upstream side of said valve member and further connected to an exhaust line, said four-way valve means in one position opening the connection in said exhaust means from the second said chamber to said pressure responsive valve means while closing the last said pipe line connection and exhaust line and in another position connecting the second said chamber to the last said pipe line connection while closing the exhaust means and exhaust line, and in still another position connecting the second said chamber to the exhaust line while closing the last said pipe line connection.

16. A pressure control apparatus comprising a valve member adapted to be placed in a hollow valve body having an inlet and an outlet connected in a pipe line on the high-pressure side of a choke, said valve member being adapted in one position to close the passage through said body and in another position to open said passage, closing means for moving the valve member to closed position including an expansible chamber having a movable wall, opening means for moving said valve member to open position comprising an expansible chamber having a movable wall, the first said wall being of smaller area than the second said wall, means associating the two said walls and said valve member to cause movement of each of the three to at least tend to move at least one of the others with the movement of each wall upon expansion of the chamber of which it is a part opposing like movement of the other wall, means for connecting the first said chamber to said pipe line on the upstream side of said valve member, means for connecting the second said chamber to the pipe line on the downstream side of said choke, the last said means including a choke, secondary valve means controlling the last said means closing the connection when the movable wall of the second said chamber is in position corresponding to closed position of said valve member and opening the connection when the last said wall has moved away from its last said position, relief means for connecting the second said chamber to atmosphere, auxiliary valve means in said re-

lief means interlocked with said movable wall of the second said chamber, said auxiliary valve means closing said relief means when the last said movable wall is in position corresponding to open position of said valve member and opening said relief means when the last said movable wall has moved away from its last said position, exhaust means for connecting the second said chamber to the atmosphere, pressure responsive valve means in said exhaust means normally closing the exhaust means but adapted to open the exhaust means on increase in pressure above a predetermined amount, a pressure responsive device connected to said exhaust means upstream from said pressure responsive valve means to indicate the position of said valve member, and four-way valve means disposed in said exhaust means between the second said chamber and said pressure responsive valve means and also connected to said pipe line on the upstream side of said valve member and further connected to an exhaust line, said four-way valve means in one position opening the connection in said exhaust means from the second said chamber to said pressure responsive valve means while closing the last said pipe line connection and exhaust line and in another position connecting the second said chamber to the last said pipe line connection while closing the exhaust means and exhaust line, and in still another position connecting the second said chamber to the exhaust line and exhaust means while closing the last said pipe line connection.

17. In apparatus including a pipe line, a valve body in the pipe line having an inlet connected to the upstream side of the line and an outlet connected to the downstream side of the line, the improvement comprising a valve member in said valve body, means responsive to upstream pressure to close the valve, said valve closing means comprising an expansible chamber having a movable wall, said chamber being connected to means to vary the pressure therein in accordance with changes in the upstream pressure in said line, means responsive to downstream pressure to open the valve, said valve opening means comprising an expansible chamber having a movable wall of larger effective area than the first said wall, the second said chamber being connected to means to vary the pressure therein in accordance with changes in the downstream pressure in said line, means associating said two walls and valve member to cause movement of any one of the three to at least tend to move at least one of the others and with the movement of each wall upon expansion of the chamber of which it is a part opposing like movement of the other wall, and means responsive to increase of downstream pressure to lower the pressure in the second said chamber below normal downstream pressure.

18. A pressure control apparatus comprising a valve member adapted to be placed in a valve body having an inlet and an outlet to control the passage of fluid therethrough, means to move the valve member to closed position including an expansible chamber having a movable wall, means to move the valve member to open position including an expansible chamber having a movable wall of larger effective area than the first said wall, means associating the two said walls and said valve member to cause movement of any one of the three to at least tend to move at least one of the others and with the movement of each wall upon expansion of the cham-

ber of which it is a part opposing like movement of the other wall, means to connect the first said chamber to a source of pressure, means to connect the second said chamber to a source of lower pressure, means responsive to closing movement of said valve member to close off said means to connect the second said chamber to a source of lower pressure, and means responsive to closing movement of said valve member to open said second chamber to atmosphere.

19. A pressure control apparatus comprising a valve member adapted to be placed in a valve body having an inlet and an outlet to control the passage of fluid therethrough, means to move the valve member to closed position including an expansible chamber having a movable wall, means to move the valve member to open position including an expansible chamber having a movable wall of larger effective area than the first said wall, means associating the two said walls and said valve member to cause movement of any one of the three to at least tend to move at least one of the others and with the movement of each wall upon expansion of the chamber of which it is a part opposing like movement of the other wall, means to connect the first said chamber to a source of pressure, means to connect the second said chamber to a source of lower pressure, means responsive to increase of pressure in said second chamber to open said second chamber to a space of still lower pressure than the said lower pressure, and means responsive to closing movement of said valve member to close off said means to connect the second said chamber to a source of lower pressure.

20. A pressure control apparatus comprising a valve member adapted to be placed in a valve body having an inlet and an outlet to control the passage of fluid therethrough, a valve stem connected to said valve member, closing means for moving the valve member to closed position including a cylinder of small cross-sectional area and a piston slideable axially therein, opening means for moving the valve member to open position comprising a cylinder of large cross-sectional area and a piston slideable axially therein, said pistons being associated with each other and said valve stem with their axes parallel so that said opening means opposes said closing means with respect to control of the position of the valve member, means for connecting the operating space in the small-area cylinder to a source of pressure, means for connecting the operating space in the large-area cylinder to a source of lower pressure, relief means for connecting the operating space in the large-area cylinder to atmosphere, said relief means including a channel through the stem of the piston in the low pressure cylinder, one end of said channel nearest the head of the piston always communicating with the operating space in the large-area cylinder, and means cooperating with the other end of the channel to close said channel when said piston in the low-pressure cylinder is in a position corresponding to full opening of the valve member.

21. In apparatus for controlling flow of fluid through a conduit, said apparatus comprising a valve body having a flow passage therethrough connected into said conduit to form therewith a continuous flow line, said valve body having an opening therein extending from the exterior thereof into said flow passage, and a choke in said line to cause a drop in the pressure of fluid flowing through the line from a higher pressure on the upstream side of said apparatus to a lower

pressure on the downstream side of said apparatus, the improvement comprising a valve member adapted to be positioned in said valve body in one position to close the passage therethrough and in another position to open said passage, a valve bonnet adapted to close said valve opening, means to seal said bonnet to said valve body, said bonnet having a stem opening therethrough, a valve stem passing through said stem opening and movable therein and connected to said valve member, means to seal between said stem and said stem opening, means to move said valve member to closed position including a cylinder and a piston slideable axially therein, means to move said valve member to open position comprising a cylinder of larger diameter than the first said cylinder and a piston slideable axially therein, means connecting said pistons to said valve stem, means to connect one part of the first said cylinder to said upstream part of the line to expose one side of said piston therein to said higher pressure, means to connect another part of the first said cylinder to atmosphere to constantly expose the other side of said piston therein to atmospheric pressure, means to connect one part of the second said cylinder to said downstream part of the line to expose one side of said piston therein to said lower pressure, and means to connect another part of the second said cylinder to atmosphere to constantly expose the other side of said piston therein to atmospheric pressure.

22. In apparatus including a pipe line, a valve body in the pipe line having an inlet connected to the upstream side of the line and an outlet connected to the downstream side of the line, the improvement comprising a valve member in said valve body, means responsive to upstream pressure to close the valve, said valve closing means comprising an expansible chamber having a movable wall, said chamber being connected to means to vary the pressure therein in accordance with changes in the upstream pressure in said line, means responsive to downstream pressure to open the valve, said valve opening means comprising an expansible chamber having a movable wall of larger effective area than the first said wall, the second said chamber being connected to means to vary the pressure therein in accordance with changes in the downstream pressure in said line, means associating said two walls and valve member to cause movement of any one of the three to at least tend to move at least one of the others and with the movement of each wall upon expansion of the chamber of which it is a part opposing like movement of the other wall, relief means connecting said second expansible chamber to a source of pressure lower than said downstream pressure, auxiliary valve means in said relief means to control flow through said relief means, means to cause said auxiliary valve means to be closed when said valve member is in its full open position and to cause said auxiliary valve means to open when said valve member moves toward open position.

23. In apparatus for controlling flow of fluid through a conduit, said apparatus comprising a valve body having a flow passage therethrough connected into said conduit to form therewith a continuous flow line, said valve body having an opening therein extending from the exterior thereof into said flow passage, and a choke in said line to cause a drop in the pressure of fluid flowing through the line from a higher pressure on the upstream side of said apparatus to a lower pressure on the downstream side of said appa-

ratus, the improvement comprising a valve member adapted to be positioned in said valve body in one position to close the passage therethrough and in another position to open said passage, a valve bonnet adapted to close said valve opening, means to seal said bonnet to said valve body, said bonnet having a stem opening therethrough, a valve stem passing through said stem opening and movable therein and connected to said valve member, means to seal between said stem and said stem opening, means to move the valve member to closed position including an expandible chamber having a movable wall, means to move the valve member to open position including an expandible chamber having a movable wall of larger effective area than the first said wall, means associating the two said walls and said valve stem to cause movement of any one of the three to at least tend to move at least one of the others and with the movement of each wall upon expansion of the chamber of which it is a part opposing like movement of the other wall, means to connect the exterior surface of each of said movable walls, that is, the surface outside of the respective chamber, to atmosphere at all times, means to connect the first said chamber to the upstream of said line, means to connect the second said chamber to the downstream part of said line, and means responsive to closing movement of said valve member to close off said means to connect the second chamber to the downstream part of said line.

24. A pressure control apparatus comprising a valve member adapted to be placed in a valve body having an inlet and an outlet to control the passage of fluid therethrough, means to move the valve member to closed position including an expandible chamber having a movable wall, means to move the valve member to open position including an expandible chamber having a movable wall of larger effective area than the first said wall, means associating the two said walls and said valve member to cause movement of any one of the three to at least tend to move at least one of the others and with the movement of each wall upon expansion of the chamber of which it is a part opposing like movement of the other wall, means to connect the first said chamber to a source of pressure, means to connect the second said chamber to a source of lower pressure, means responsive to increase of pressure in said second chamber to open said second chamber to a space of still lower pressure than the said lower pressure, and means separate from the last said means and responsive to closing movement of said valve member to first open said second chamber to a space of still lower pressure than said lower pressure and thereafter to close off said means to connect the second said chamber to a source of lower pressure.

25. In apparatus for controlling flow of fluid through a conduit, said apparatus comprising a valve body having a flow passage therethrough connected into said conduit to form therewith a continuous flow line, said valve body having an opening therein extending from the exterior thereof into said flow passage, and a choke in said line to cause a drop in the pressure of fluid flowing through the line from a higher pressure on the upstream side of said apparatus to a lower pressure on the downstream side of said appa-

ratus, the improvement comprising a valve member adapted to be positioned in said valve body in one position to close the passage therethrough and in another position to open said passage, a valve bonnet adapted to close said valve opening, means to seal said bonnet to said valve body, said bonnet having a stem opening therethrough, a valve stem passing through said stem opening and movable therein and connected to said valve member, means to seal between said stem and said stem opening, means to move said valve member to closed position including a cylinder and a piston slidably axially therein, means to move said valve member to open position comprising a cylinder of larger diameter than the first said cylinder and a piston slidably axially therein, means connecting the second said cylinder to the valve bonnet, means integral with said second cylinder closing one end thereof, a piston rod passing through the other end of said second cylinder and connected at one end to said piston therein and at the other end to said valve stem, said first cylinder being disposed inside second cylinder with one end of said first cylinder abutting against said closed end of the second cylinder, means to releasably secure said first cylinder in said second cylinder, means to seal between said one end of said first cylinder and said closed end of said second cylinder, a piston rod passing through the other end of said first cylinder and connected at one end to said piston therein and at the other end to said piston in the second cylinder, means to connect the part of the first said cylinder on that one side of the piston therein in adjacent said sealed end thereof to said upstream part of the line to expose said one side of the piston to said higher pressure, means to connect the second said cylinder on that one side of the piston therein that is connected to the valve stem to said downstream part of the line to expose said one side of the piston therein to said lower pressure, and a port to atmosphere through the second said cylinder between the other side of the piston therein and the other side of the piston in the first cylinder.
